[57] CLAIM

The ornamental design for a pull tab for a slide fastener slider, as shown and described.

DESCRIPTION

FIG. 1 is a front view of the ornamental design of the pull tab for a slide fastener slider in accordance with our invention;

FIG. 2 is a plan view of the pull tab of FIG. 1;

FIG. 3 is a base view of the pull tab of FIG. 1;

FIG. 4 is a rear view of the pull tab of FIG. 1;

FIG. 5 is a left side view of the pull tab of FIG. 1;

FIG. 6 is a right side view of the pull tab of FIG. 1;

FIG. 7 is a cross-sectional view taken on line VII—VII of FIG. 1;

FIG. 8 is a cross-sectional view taken on line VIII—VIII of FIG. 1;

FIG. 9 is an enlarged cross-sectional view taken on line IX—IX of FIG. 1; and,

FIG. 10 is an explanatory view showing the pull tab of FIG. 1 in use.

The broken line showing of a slide fastener slider in FIG. 10 is for illustrative purposes only and forms no part of the claimed design.
